Patented Feb. 10, 1914.

UNITED STATES PATENT OFFICE.

HARRY W. BROWN, OF SEATTLE, WASHINGTON.

MONORAIL-CAR.

1,086,890.

Specification of Letters Patent. Patented Feb. 10, 1914.

Application filed March 17, 1913. Serial No. 755,013.

To all whom it may concern:

Be it known that I, HARRY W. BROWN, a citizen of the United States, and a resident of Seattle, in the county of King and State of Washington, have invented certain new and useful Improvements in Monorail-Cars, of which the following is a specification.

This invention relates to monorail cars, and has for its principal object to provide improved means whereby undue friction is avoided between the traction wheel and the rail.

Further objects will appear as the invention is more fully described in the following specification, illustrated in the accompanying drawings, and pointed out in the appended claims.

In the drawings, Figure 1 is a fragmentary side elevation of the track and its supporting structure, with a car thereon. Fig. 2 is a sectional view upon the line $\alpha-\alpha$ of Fig. 1. Fig. 3 is an enlarged detail view of one of the plates upon which the car springs are mounted.

Referring now more particularly to the drawings, reference character A, designates, in a general way, one of the ground supports for the track, consisting of the cross timber 1, supported upon the piles 2; the vertical timber 3, secured to the said cross timber, and the side braces 4, the lower ends of which are secured to the said cross timber and their upper ends bear against the angle irons 5, secured to the said vertical timber 3.

The said vertical timber may be further reinforced by the braces 6. It will be, of course, understood that ground supports similar to that just described, occur at suitable intervals, and upon the upper ends of the vertical timbers 3 is the track proper, preferably of the laminated form, as shown and which is indicated at 7. Upon the track 7 is the rail 8, substantially of U shape, in cross section, as shown, and upon which the wheel 9 rests, the face of the said wheel being slightly convex (see Fig. 2). The ends of the axle 10 are revolvably mounted in suitable journal bearings in the blocks 11, which slide vertically within the recesses 12 in the casting 13, the said recesses being channeled in the direction of their length, as indicated by the dotted line in Fig. 1. Within the said recesses slide the plates 14, the extensions 15 of which slidably fit into the said channels,

as will be understood. Upon the plates 14 are the studs 16 which project into the helical springs 17, the uppermost plate 14 being held in position by the cap 18, through which passes the threaded bolt 19. By the means described, the casting 13, with its associated parts, is yieldingly mounted upon the axles 10. Revolvably passing through the casting 13, from side to side, are the shafts 20, upon which are mounted the rollers 21. Extending downwardly from each side of the casting 13 are the members 22, which are joined together, at their bottoms, by the member 23. Extending outwardly from one pair of the said members 22, are the projections 24, upon which are yieldingly mounted, as by means of the springs 25, the blocks 26, through which blocks revolvably pass the axles 27 of the wheels 28, the upper pair of which contact with the sides of the track 7, and the lower pair contact with the stringers 29, secured to the vertical timber 3. Extending outwardly from the member 23 are the arms 30, the outer ends of which are connected by the strip 31. Through the arms 30 pass the bolts 32, which are yieldingly held in the positions shown by the springs 33. To the lower ends of the said bolts are secured the members 34, upon the upper side of which is the ball 34a which fits into a suitable socket in the boss 35, upon the lower side of the car 36, in which may be the window 37, and from which downwardly extend the side boards 38.

It may or may not be old in the art to employ a wheel substantially of the same formation as that shown at 9, but which has a rubber or other resilient face, adapted to run upon a flat faced rail; but the disadvantage of such construction is apparent in that unnecessary friction is created between the wheel and its rail, and especially is this true in rounding curves. About the same objections apply to the use of an ordinary double flanged wheel for this purpose. It is clear that in my improved construction, two points of contact only exist between the wheel 9 and its rail 8, due to which the friction between the wheel and its rail is reduced to a minimum, and especially is this true when the car is rounding a curve in the track. This reduction to a minimum of the friction is more apparent when it is considered that but one wheel—9, is used, in conse-

quence of which any vertical movement of the ends of the axle 10 simply causes the convex face of the wheel 9 to wipe against the two contacting points of the rail 8, without undue binding which, would, of course, occur to a greater or less extent if two such wheels were employed side by side on parallel tracks.

From the foregoing it is believed that the construction and operation of my device will be fully understood by others, and, while I have shown a particular form of car body, supporting structure and other details, I am fully aware that many changes in the same may be made, without departing from the spirit and scope of my invention, and I do not, therefore, desire to be limited to the exact form of embodiment hereinabove described and shown in the accompanying drawings.

What I claim as new and desire to protect by Letters Patent, is—

1. The combination with the car, track and its supporting structure, of a monorail system, of a single convex faced traction wheel for the car, and a rail having a single point of contact with the face of the said wheel and at each side of the vertical center thereof.

2. The combination with the car and track supporting structure of a monorail system, of a laminated track upon the said structure, a rail secured to the said track, the said rail being of substantially U shape in cross section, and a single convex faced traction wheel for the car.

HARRY W. BROWN.
